UNITED STATES PATENT OFFICE

LEWIS M. CROSLEY, OF CINCINNATI, OHIO, ASSIGNOR TO THE CROSLEY RADIO CORPORATION, OF CINCINNATI, OHIO, A CORPORATION OF OHIO

REFRIGERATING DEVICE

Application filed November 19, 1928. Serial No. 320,312.

My invention relates to the use of retarding devices for use with absorption refrigeration systems, particularly those which require removal of the refrigeration unit from the refrigerator for purposes of regeneration.

In the absorption system of refrigeration it is an advantage to effect generation as rapidly as possible, and refrigeration as slowly as possible, to maintain the required temperature. The cold reaction upon the condenser-evaporator within a refrigerator box is not sufficient to retard the evaporation of refrigerant, and this is particularly true in the instance of boxes which are frequently opened on hot days and in hot climates. The retarding of the cold cycle is accomplished by preventing contact of the evaporator element with bodies, gases or liquids which will supply heat of vaporization, and it results not only in keeping a more regular temperature in the refrigerator but where the outside temperature is high, it helps to maintain a pressure differential, which, if not present, might result in the pressure in the absorber building up sufficiently to prevent absorption.

Thus, in the very hot desert regions of this country, absorption systems have not been successful because of the premature striking of a balance of pressures due to the high heating of the generator-absorber.

Among other objects of my invention is providing as a preferred type of retarder a device containing a brine, which brine becomes quite cold, and during the period when generation is taking place, will keep the interior of the box from rising too high. In systems requiring removal of the unit, this is particularly valuable.

I have devised a retarder which is mechanically arranged for use quite conveniently with the refrigeration unit of David Forbes Keith's application for Letters Patent Serial No. 201,904, filed June 27th, 1927. Thus, the construction and mode of support is such as to take care of inaccuracies of adjustment and still properly insulate and retard the evaporation in the cold ball.

The above and other advantages accomplished by my invention are exemplified in

the construction shown and described in the following subject matter.

In the drawings:

Figure 1 is a sectional view of a refrigerator showing my invention in use.

Figure 2 is a perspective of a brine tank used as a retarder.

I have indicated a refrigerator cooling box 1, which has a lid 2 and a slot in the side wall of the box as at 3, for retaining the refrigerator unit in place.

The unit selected for illustration has a generator-absorber chamber or ball 4, and a condenser-evaporator chamber or ball 5. The two are connected by a tubular casing 6, which 65 serves to enclose all connections between the two balls, and when the device is in use is set into the receiving slot in the side wall of the box, whereupon the lid can be closed down over it, leaving the condenser-evaporator 70 within the box.

A preferred type of retarder, which is illustrated, is in the form of a rectangular vessel 7, with one curved side, having soldered into the top thereof a hemispherical enclosing plate 8. A fitting 9 in the top of the vessel serves for filling it with brine or other non-freezing fluid.

In order to expose the ice drawer in the condenser-evaporator ball, the hemispherical 80 top plate and the side wall of the vessel are cut away and a piece inserted as at 10, to form a notch in the vessel which will expose the drawer.

The shape of the vessel top will be such 85 as to receive the condenser-evaporator shell. It happens that in the particular condenser-evaporator ball shown, there is a hood 11 supported on the ball, serving as a water circulation shell around the upper half of the 90 ball during the condensation portion of the cycle of the device. The shape of the vessel top is such as to permit this hood to come down close to the top of the vessel.

In an instance wherein the condenser-evaporator carries no hood, it may be desirable to drop a hood over the ball or casing to impart additional insulation thereto.

The vessel is in the preferred form of device, supported on feet formed of short posts 100

12, set onto the base of the vessel and surrounded by coiled springs 12a which extend further than the posts, and thus form spring feet for the vessel.

5 This arrangement will permit the vessel to accommodate itself to the particular positions of the evaporator ball, and slight differences in construction, length of connecting arm, etc., so that there is no air space 10 left between the bottom half of the ball and the retarder.

Instead of filling the retarder with brine or some element to retain the cold, partial results can be gained by merely providing 15 the vessel itself, or a hood, omitting the feet, which rests on the base of the box and receives the ball. In such instance the hemispherical top closure plate would be omitted, and the retarding would be due to the elimination of a large part of the air circulation 20 around the ball.

Of course, the shape of the vessel and its top plate, or the shape of an enclosing hood or the like, will be so arranged as to take 25 whatever shape of refrigeration unit as may be employed and I do not wish to limit myself to a device which will take a ball since the invention has broader aspects.

Having thus described my invention, what 30 I claim as new and desire to secure by Letters Patent, is:—

1. In an absorption system refrigeration device comprising a cooling box and a removable unit having, when installed with the 35 cooling box, a generator-absorber outside the cooling box, and a condenser-evaporator inside the cooling box, solid surfaced means within the box for retarding absorption of heat by said condenser-evaporator.

40 2. In an absorption system refrigeration device comprising a cooling box and a removable unit having, when installed with the cooling box, a generator-absorber outside the cooling box, and an internal condenser- 45 evaporator inside the cooling box, means within the box for retarding absorption of heat by said condenser-evaporator, said means comprising a closed shell surrounding said condenser-evaporator at least in part.

50 3. In an absorption system refrigeration device comprising a cooling box and a removable unit having, when installed with the cooling box, a generator-absorber outside the cooling box, and an internal condenser- 55 evaporator inside the cooling box, means within the box for retarding absorption of heat by said condenser-evaporator, said means comprising a closed container within which a substance retentive of cold is held.

60 4. In an absorption system refrigeration device comprising a cooling box and a removable unit having, when installed with the cooling box, a generator-absorber outside the cooling box, and an internal condenser- 65 evaporator inside the cooling box, means

within the box for retarding absorption of heat by said condenser-evaporator, said means comprising a closed container within which a substance retentive of cold is held, said container surrounding the condenser- 70 evaporator, at least in part.

5. A retarder for use with the condenser-evaporator of a removable refrigeration unit, comprising a vessel filled with brine or similar substance, having a top portion 75 which is shaped to receive within it a substantial portion of the said condenser-evaporator.
